UNITED STATES PATENT OFFICE.

JOHN L. NICHOLSON, OF CHICAGO, ILLINOIS, ASSIGNOR TO LOCOMOTIVE FIREBOX COMPANY, OF CHICAGO, ILLINOIS, A CORPORATION OF DELAWARE.

EXPANSION AND CONTRACTION ANCHORAGE FOR THERMIC SIPHONS.

Application filed February 21, 1922. Serial No. 538,410.

This invention relates to locomotive boilers which contain such water steaming and circulating devices, as I have described and claimed in Letters Patent No. 1,337,720, granted April 20, 1920. The device mentioned is known as the Nicholson thermic siphon. It is generally of triangular form, having at the bottom or inverted apex, an intake neck or tubular portion which extends through the front wall or throat sheet of the firebox. The inverted base of this triangular water wall, for such it is, opens through and is attached to the crown sheet of the firebox. Obviously all connections must be strong and steam tight.

The thermic siphon, as is the case with all other parts of the firebox, is subjected to very considerable expansion and contraction movements, due to the varying temperature within the firebox. These movements and stresses tend to disrupt the joints between the thermic siphon and throat and crown sheets, making it necessary, as pointed out in the aforesaid patent, to provide means to automatically take up or absorb these movements of expansion and contraction.

This present invention has to do with improvements in the connection between the neck or intake end of the siphon and the flue sheet, or throat sheet, of the firebox.

Hitherto I have employed a diaphragm section or portion surrounding the neck of the siphon, forming the same either in the sheet itself or first cutting a hole in the sheet and then welding in, and separately staying the diaphragmic section. As will presently appear, I propose now to modify that sort of connection by providing the forward part of the firebox itself with a special protuberance and cavity, added to the throat or front water leg of the firebox, and which will directly receive the neck of the siphon.

The general construction herein mentioned, and the details of my invention, will be readily understood on reference to the accompanying drawings, in which I have illustrated several of the forms in which my invention may be applied. In said drawings:

Figure 1 is a longitudinal vertical section of a locomotive firebox containing my invention; Fig. 2 is a partial horizontal section thereof on the line 2-2 of Fig. 1; Fig.

3 is a somewhat enlarged front elevation of the device which I apply to the front sheet, one for each thermic siphon; and Figs. 4 and 5 illustrate modified forms of the device, or as might better be said, represent different ways in which the device of Fig. 3 may be applied to fireboxes of various shapes.

The firebox illustrated in Fig. 1, is of the straight flue sheet type, except that the throat sheet 2, is pitched downward and backward, as contrasted with the plain throat of Fig. 5. Figure 4 represents a portion of the firebox of the so-called combustion chamber type, having a throat sheet 4 which at the top merges with the combustion chamber portion 5 of the firebox. The firebox, according to size, contains one, two or three thermic siphons S, of the form above described and extending from the throat sheet 2, to the crown sheet 6, in each case.

This generally triangular and hollow water wall expands and contracts within, and with, the firebox, and I have observed that such movement culminates in the neck S' of the siphon, and seems to take effect, accumulatively, along the line of the middle axis (imaginary) 7, of the siphon. In consequence, in every case, the direction of the expansion and contraction movement between the neck of the siphon and throat sheet is observed to conform to a line which extending from the crown sheet forms an acute angle with the throat sheet.

I conceive that the proper position for the diaphragmic connection between the throat sheet and the neck of the siphon, should be in a plane perpendicular to this resultant or accumulative line of expansion and contraction between the parts. To accomplish this without greatly complicating the problem of staying the boiler sheets, I employ an inverted cylindrical pot, 8, the lower end of which opens, so to speak, through the throat sheet of the firebox, and hence into the front water leg of the boiler, while the upper end of the pot 8 contains a central opening and is formed or corrugated in such a manner as to successfully accomplish the purposes of a diaphragm, to which the lower end of the siphon is permanently fastened, as by the autogenous welding process.

This pot 8, I have further arranged, with

its axis in alignment or substantially in alignment with the middle or resultant line of expansion and contraction, as represented by the line 7, in Figs. 1, 4 and 5. Obviously 5 that imaginary line as found in different siphons, varies in position and inclination according to their differences in triangular shape.

The inverted pot 8, is pressed, stamped or 10 forged from a sheet of rolled material like the fire sheets of the firebox, generally steel or copper. Obviously it is possible to use a copper pot in a steel firebox.

In order that its upper end may be bulged 15 or corrugated, as shown at 8', the inverted pot 8, as well shown in Figs. 2 and 3, is of generally cylindrical form and of about twice the diameter of the intake neck S' of the thermic siphon, to the end that its upper 20 end 8' may contain the central opening 9, for the siphon neck.

In applying this device I first form or cut 25 an opening in the throat sheet, making the same somewhat larger than the diameter of the pot 8 and then, having ascertained the correct-angular position for the inverted pot, I truncale and flange the lower end thereof, on a plane corresponding to such angular position. I then provide it with a 30 flange 8'', which I fit within the opening previously formed in the throat sheet. Having done this, and before the siphon is fitted into the firebox, I apply the inverted pot to the lower end of the siphon, adjust it to the 35 correct position thereon (not in alignment with the bulged lower part of the siphon, but in alignment with the ascertained resultant expansion and contraction line or axis 7) and then weld the inwardly turned 40 central flange 8'' of the pot to the siphon neck. I then place the siphon in the firebox, following the method generally described in the aforesaid Letters Patent, welding or riveting the flanged base 8'', of 45 the inverted pot to the throat sheet. It then only remains to apply stay bolts 10, to the base flanges and walls of the inverted pot; these stay bolts, as will be apparent, being 50 made fast in the shell of the boiler. Various other stay bolting methods may be employed as indicated in Figs. 1, 4 and 5.

I prefer that in every case the plane of truncation (the plane upon which the inverted part is made to conform to the throat 55 sheet), shall intersect the highest point of the bulging or corrugated top 8' of the inverted pot, thus to avoid the presence of a steam pocket therein. The correct position for the diaphragm part, or in that case the 60 inverted pot, is not difficult to determine. The mean line of expansion and contraction (herein called resultant), is a line which bisects the angle of the siphon, treating the

end of the neck S' as the apex and the top of the siphon as the base of the bisected 65 angle.

These relatively small protuberances on the throat sheet do not interfere with the operation of the firebox grate, nor do they tend to interfere with or suppress combustion on the forward end of the grate. The construction has the further merit of being inexpensive, easy of application, very durable, and entirely safe.

Having thus described my invention, I 75 claim as new and desire to secure by Letters Patent:

1. A locomotive firebox embodying there- 80 in a throat sheet and containing a thermic siphon having a neck, the line of expansion and contraction of said siphon extending at an acute angle to said throat sheet, an inverted cylindrical pot incorporated in said throat sheet with its axis in substantial alignment with said line of expansion and 85 contraction and having a wall with an opening therein to receive the end of said neck.

2. A locomotive firebox embodying there- 90 in a throat sheet and containing a thermic siphon having a neck, the line of expansion and contraction of said siphon extending at an acute angle to said throat sheet, and an inverted cylindrical pot incorporated in said throat sheet and having a wall with a flanged opening therein to receive said siphon neck, which wall is perpendicular to said line of 95 expansion and contraction of the siphon.

3. A locomotive firebox embodying there- 100 in a throat sheet and containing a thermic siphon having a neck, the line of expansion and contraction of said siphon extending at an acute angle to said throat sheet, and an inverted cylindrical pot incorporated in said throat sheet and having an annularly corrugated wall with a flanged opening therein to 105 receive said siphon neck, which annularly corrugated wall is disposed perpendicular to said line of expansion and contraction of the siphon.

4. The improvements herein described 110 comprising in combination with a locomotive firebox having crown and throat sheets, a water steaming and circulating element having an elongated top end opening through said crown sheet and having a neck at its other end, the line of expansion and contraction of said element extending at an acute angle to said throat sheet, an inverted cylindrical pot incorporated in said throat sheet, and having a wall in which said neck is received which wall is perpendicular to said line of expansion and contraction of the 115 said element.

In testimony whereof, I affix my signature.

JOHN L. NICHOLSON.
